UNITED STATES PATENT OFFICE.

HENRY F. KING, OF BUFFALO, NEW YORK.

THILL-COUPING.

SPECIFICATION forming part of Letters Patent No. 253,066, dated January 31, 1882.

Application filed June 9, 1881. (No model.)

To all whom it may concern:

Be it known that I, HENRY F. KING, a citizen of the United States, residing at Buffalo, in the county of Erie and State of New York, 5 have made certain Improvements in Thill-Couplings, of which the following is a specification.

This invention relates to a double clip around the axle, and also to improvements in the 10 tightening-spring to better prevent rattling, all as hereinafter fully explained.

In the drawings, Figure 1 is a side elevation of the device, the wooden axle in section; Fig. 2, a front view, showing the double clips, 15 &c.; Fig. 3, bottom view of spring and base.

A A' represent the ordinary wooden and iron axle and inclosed by two shackles or clips, B B, and between which the round rear end, e, of the thill C is fastened, as shown in Fig. 20. These clips also hold a curved C-spring, D, which rounds from the bottom and back of the axle, over the top and front thereof. It is attached to or forms part of a flat cross-piece, a, which, with the spring D, sets against the 25 under side of the axle, and has two outside cross-pieces, b b, also forming part of the piece a and spring D, through which the ends B' B' of the clips go, with nuts c c thereon. These nuts c c prevent any loosening and allow of a 30 continual tightening up if the clips become at all loose, while the bottom piece, a, of the spring D, of which it forms a part, with the side pieces, b b, keep the spring from any side play.

Two shackles or clips are employed instead

of one, as is customary, as for heavy wagons 35 especially the thill will be held better and more firmly, and the bolt d, that goes through the thill-eye, with a solid head on one end and a screw-nut on the other, can be tightened by the nut as often as wear occurs without taking the clip off, as has to be done with the single clips.

The improvement in the spring D (the spring being old) consists in making a cup-shaped end, D', (see Fig. 1,) which sets against and 45 partly incloses the round rear end, e, of the thill, and thus prevents the jarring and noise consequent on the use of springs of this curved character when the flat end merely presses against the rear of the thill, and which causes 50 the very rattling which they are intended to prevent.

My improvement is important, as it greatly strengthens the coupling and effectually prevents rattling.

I claim—

In a thill-coupling, the double clips B B and the spring D in combination therewith, the spring constructed with the cup-shaped end D', partly inclosing the rear end of the thill e, 60 substantially as and for the purpose specified.

In witness whereof I have hereunto signed my name in the presence of two subscribing witnesses.

HENRY F. KING.
